United States Patent Office

Des. 186,916

Patented Dec. 22, 1959

186,916

HAND OPERATED VIEWER OR SIMILAR ARTICLE

Egbert B. Close, Philadelphia, and Joseph A. Patenaude, Devon, Pa., assignors to C & P Phonoproducts, Incorporated, Philadelphia, Pa., a corporation of Pennsylvania

Application September 11, 1958, Serial No. 52,615

Term of patent 14 years

(Cl. D61—1)

FIG.1.

FIG.2.

FIG.3.

FIG.5.

FIG.4.

Fig. 1 is a front perspective view of a hand operated viewer or similar article, showing my new design;

Fig. 2 is a rear perspective view;

Fig. 3 is a top plan view, the bottom being substantially a mirror image thereof;

Fig. 4 is a front elevational view thereof; and

Fig. 5 is a rear elevational view thereof.

We claim:

The ornamental design for a hand operated viewer or similar article, as shown and described.
